UNITED STATES PATENT OFFICE.

JOSEPH M. RIBERT, OF NEW YORK, N. Y., ASSIGNOR TO NATIONAL NOVELTY CORPORATION, OF NEW YORK, N. Y., A CORPORATION OF NEW JERSEY.

LEMON-SQUEEZER.

SPECIFICATION forming part of Letters Patent No. 783,893, dated February 28, 1905.

Application filed October 5, 1904. Serial No. 227,261.

To all whom it may concern:

Be it known that I, JOSEPH M. RIBERT, a citizen of the United States, residing at New York city, in the county of New York, State of New York, have invented certain new and useful Improvements in Lemon-Squeezers, of which the following is a description, reference being had to the accompanying drawings and to the letters of reference marked thereon.

10 My invention relates to lemon-squeezers—that is, devices for expressing the juice from lemons, limes, or other fruit for use in beverages or for other purposes—and relates particularly to the class of such devices adapted to be secured to a bar-top or table-top and to be operated by a handle.

20 My invention has for its object to provide a construction of such device which shall be simple and inexpensive to construct and shall be durable and efficient in operation, and particularly to so form the parts of the device that they may be made, so far as possible, by casting without the necessity for machining.

25 With these objects in view my invention consists in the construction and combination of elements hereinafter described, and particularly pointed out in the claims.

Referring to the drawings, Figure 1 is a side elevation of a lemon-squeezer embodying my 30 invention. Fig. 2 is a vertical sectional view showing the working parts of the device. Fig. 3 is a plan view of the removable cup carrying the lower member of the squeezing device. Fig. 4 is a detail perspective view of the rack. Figs. 5, 6, 7, and 8 are detail views showing the construction of the operating-screw, Figs. 5 and 8 showing the parts assembled, and Figs. 6 and 7 showing, respectively, the upper and lower castings. Fig. 9 35 is a horizontal sectional view on line 9—9 of Fig. 1.

In the drawings, A is the main bracket, formed of a single casting, having rearwardly-extending arms B and C, the arm B being 40 adapted to rest on the top of a bar top or table-top and the arm C being adapted to receive a clamping-screw D, between which and the arm B the bar-top or table-top may be firmly gripped. From the arm B the bracket A ex-

tends upward and forward and at its end is 50 provided with a vertical portion A', through which are formed ways A'', communicating with which is a longitudinal recess A''. A recess A''' communicates with the rear of the recess A''. 55

In the recess A''' is arranged a vertically-sliding rack J, having at its upper and lower ends lugs J' J'', adapted to fit and slide in the ways A''. A gear-wheel K, journaled in the walls of the recess A'', is arranged to rotate 60 in the recess A'', in mesh with the rack J. An operating-handle R is connected with the gear K for operating it. In the lugs J' J'' is journaled the plunger-rod H, carrying at its lower end the plunger I. On the rod H between 65 the lugs J' J'' is secured the cam S, having formed therein a cam-groove S', the lower portion of which is straight and in line with the axis of the rod H and the upper portion of which is in the form of a screw-thread. A 70 pin T, inserted through the wall of the recess A'', is adapted to enter the cam-groove S'. As the handle R is operated to rotate the gear K the rack J will be moved downward, carrying down with it the rod H and the plunger I. As 75 the rack moves downward the cam-groove S' of the cam S is engaged by the pin T, and as the lower portion of the groove is straight the plunger will be carried directly downward for the first part of its movement. As the downward movement continues the upper part of the cam-groove is brought into engagement with the pin T, with the result that the cam S, and with it the rod H and plunger I, is given 80 a movement of rotation as well as a further 85 downward movement.

Below the arm C there is formed on the bracket A a socket L, in which is secured the upper end of a vertical rod M, on which is adjustably mounted a bracket O, held in position by a screw O', which is adapted to support the serving-glass or other receptacle to receive the juice of the fruit. On the socket L is removably secured a bracket N, which carries the projection P', with which the plunger I cooperates to press out the juice of the lemon or other fruit. The bracket N is secured in position by set-screw N' and is cup-

shaped, the walls of the cup being preferably tapered and the bottom of the cup being inclined toward a central opening n , through which the juice may be discharged into the 5 receptacle carried by the bracket O.

In the cup of the bracket N is received a cup P, provided with the central projection P', having radial grooves formed in its sides. The walls of the cup P are tapered downward, 10 as shown, leaving between them and the walls of the cup of the bracket N free space for the passage of the juice expressed from the lemon or other fruit. At its upper edge the cup P is provided with an external flange p, which 15 rests on the upper edge of the cup of the bracket N. The depth of the cup P is such that a space is left between it and the bottom of the cup of the bracket N to give free passage to the juice expressed from the fruit. 20 About the projection P' and extending upward into the sides of the cup are slits or openings p^2 of such width as to permit of the free passage of the juice without permitting the seeds to pass. The cup P being removable from the bracket N, the seeds and other 25 waste material may be readily disposed of by simply removing it and dumping its contents into an appropriate receptacle. By this arrangement all the parts coming in contact with 30 the lemon or the juice may be readily cleaned.

The plunger I is provided on its interior with radial ribs I', which as the plunger is pressed downward engage the exterior of the lemon or other fruit to be squeezed, and as the 35 plunger receives its final movement of rotation these ribs coöperate with the ribs p' of the projection P' to effect a complete expression of the juice and by bruising the exterior of the lemon breaks the oil-cells and sets free 40 the essential oil.

The cam S is made up of two castings S² and S³, both of which are so formed that their patterns may be readily drawn from a sand mold. The upper casting S² has a central 45 hub s, having a central bore in which the upper end of the rod H is secured, the hub s terminating in a shoulder s' on a plane at right angles to the axis of the rod H. The outer portion of the casting S² terminates at its 50 lower end in a shoulder s². From this shoulder s² on one side extends upward a curved edge forming the upper edge of the cam-groove S' and on the other side the edge extends upward to form a shoulder s³. The 55 lower portion of the lower casting S³ is cylindrical and has an axial opening formed therein to receive the rod H and also has a straight groove S⁴ formed in it. From one side of the upper end of this groove S⁴ the edge of the 60 casting extends upward in a curve which forms the lower edge of the cam-groove S'. On the opposite side of the upper end of the groove S⁴ is formed a shoulder s⁴, preferably adapted to receive the shoulder s², and from the edge 65 of this shoulder the casting extends upward

to form a curved shoulder S⁵, adapted to fit the shoulder s³. At its upper end the lower casting has formed therein a recess s⁶, adapted to receive the hub s, and having a shoulder s⁷ at its base against which the shoulder s' fits. 70 The lower portion of the lower casting S³ is preferably cut away, as shown at s⁸. When the two castings are placed together, the hub of the casting S² fits within the recess s⁶, the shoulder s' resting on the shoulder s⁷ and the shoulder s³ fits against the shoulder s⁸. A single pin or rivet s⁹, passing through the upper part of the casting S³ through the hub s and the rod H, serves to hold the castings rigidly in position and to secure them to the rod 80 H. Each can have a pin or rivet, if necessary.

When the plunger is in elevated position, the handle R rests in the position indicated in Fig. 2, holding the plunger elevated and leaving between the plunger and the projection 85 P ample space to place the half lemon or other article to be squeezed in position. As the handle is swung over its first movement, which is forward, brings the plunger downward into contact with the article to be 90 squeezed. The remainder of the movement of the handle is downward, which permits of the full strength of the operator being exerted to press the plunger downward and to give it its final movement of rotation. 95

By constructing the cam S, as above described, of two castings it can be made at very little expense.

The upper end of the ways A² and recess A³ is preferably closed by a plate. 100

Having thus described my invention, what I claim as new, and desire to secure by Letters Patent, is—

1. In a lemon-squeezer, the combination of a bracket, an arm secured to the bracket provided with means for supporting the article to be squeezed, an upper arm on the bracket having vertical ways formed therein, and a vertical recess communicating with said ways, a rack provided with lugs movable in said ways, a plunger-rod journaled in said lugs and provided with a plunger, a cam-block secured to the plunger-rod between the lugs having a cam-groove therein, a pin carried by the upper arm extending into the cam-groove, and means for reciprocating the rack; substantially as described. 110

2. In a lemon-squeezer, the combination of a bracket, an arm secured to the bracket provided with means for supporting the article to be squeezed, an upper arm on the bracket having vertical ways formed therein and a vertical recess communicating with said ways, a rack provided with lugs movable in said ways, a plunger-rod journaled in said lugs and provided with a plunger, a cam-block secured to the plunger-rod between the lugs having a cam-groove therein, said cam-block consisting of an upper casting and a lower casting firmly secured to the plunger-rod, a pin carried by 115 120 125 130 135

the upper arm extending into the cam-groove, and means for reciprocating the rack; substantially as described.

3. In a lemon-squeezer, a reciprocating plunger, a plunger-rod carrying the plunger, a rack provided with lugs in which the plunger-rod is journaled, means for reciprocating the rack, a cam-block carried by the plunger-rod between the lugs, having a cam-groove having a straight portion and a helical portion formed therein and a stationary pin extending into the cam-groove, the cam-block consisting of an upper casting having the upper edge of the helical portion of the cam-groove formed therein and the lower casting having the straight portion of the cam-groove and the lower edge of the helical portion formed therein; substantially as described.

4. In a lemon-squeezer, a reciprocating plunger, a plunger-rod carrying the plunger, a rack provided with lugs in which the plun-

ger-rod is journaled, means for reciprocating the rack, a cam-block carried by the plunger-rod between the lugs having a cam-groove having a straight portion and a helical portion formed therein, and a stationary pin extending into the cam-groove, the cam-block consisting of an upper casting having an inner hub, and having the upper edge of the helical portion of the cam-groove formed thereon, and the lower casting having the straight portion of the cam-groove and the lower edge of the helical portion formed therein, and means for securing the castings to the plunger-rod; substantially as described.

In testimony whereof I affix my signature in presence of two witnesses.

JOSEPH M. RIBERT.
